UNITED STATES PATENT OFFICE

2,347,274

PROCESS OF PRODUCING PARAFFINIC OILS

Almer M. McAfee and Edward E. Dunlay, Port Arthur, Tex., assignors to Gulf Oil Corporation, Pittsburgh, Pa., a corporation of Pennsylvania

Application April 25, 1941, Serial No. 390,376

14 Claims. (Cl. 196—9)

This invention relates to a process of producing paraffinic oils, including gasoline-like hydrocarbons of high antiknock value when used as motor fuels, high grade Diesel fuels and the like; and it comprises a method in which non-residual oils or distillates high in naphthenic and aromatic constituents are reacted with olefin-containing gases in the presence of aluminum chloride or other aluminum halide catalysts at low temperatures not exceeding about 250° F. It further comprises subjecting relatively high boiling fractions of the oils thereby produced to catalytic cracking in the presence of aluminum chloride catalysts, which may be catalyst sludge recovered from the initial reaction.

In U. S. Patent No. 1,608,328 to McAfee there is described a process of synthesizing oil in which residual oils, such as asphaltic reducing crudes and other residual oils having relatively high carbon:hydrogen ratios are subjected to contact with gases rich in hydrogen in the presence of aluminum chloride and at high temperatures, that is to say at 500° F. or higher, thereby effecting a condensation of the gases and the oils to form oils of averaged composition with lower asphaltic content. That process was distinguished from prior aluminum chloride cracking processes in a number of ways and particularly in that production of gasoline, if any, was an incidental feature rather than the principal object of the process. In cracking processes, however, gasoline production was the principal object.

Our present invention, while resembling the process of the aforesaid Patent No. 1,608,328 in that it involves treatment of oils with gases in the presence of aluminum chloride, is sharply to be distinguished from the process of said patent.

In accordance with our present invention the oils employed are non-residual and "non-asphaltic" oils intermediate in boiling range between gasoline and lubricating oil fractions; they are distillates or distillate fractions as distinguished from residual oils or reduced crudes.

The present invention, unlike the process of Patent No. 1,608,328, is not concerned with the carbon:hydrogen ratios of the reacting gases and oils; the gases may be higher or lower in carbon:hydrogen ratio than the oil. As a matter of fact, our process is especially advantageous where highly unsaturated gases, of relatively high car-

bon:hydrogen ratio, are employed. In many cases, the carbon:hydrogen ratio of the olefinic gases will be higher than the carbon:hydrogen ratio of the oil treated.

5 Referring to the oil used as one of the starting materials, we prefer to employ oils of the character generally known as solar oils, particularly those produced from coastal crudes and containing large or even predominating amounts of naphthenic and aromatic constituents. Corresponding distillates from highly paraffinic crudes, such as Pennsylvania crudes, are less suitable. As aforesaid, suitable oils are those intermediate the boiling point range of gasoline on the one hand and light lubricating oil fractions on the other hand. Straight run distillates may be employed but the invention is not so limited and we have in fact applied our invention successfully to sulfur dioxide extracts of kerosenes from 10 California and other highly asphaltic crudes. The boiling point range of the starting material will run from about 400° to 700° F.

The gases employed in accordance with our invention are olefin-containing gases such as refinery gases and particularly gases produced in cracking petroleum oils, as well as individual fractions thereof. We have found that such gases should contain at least about 30 per cent of unsaturated constituents, and preferably 50 per cent or more of unsaturates. Our invention, in one advantageous aspect, contemplates the reaction of propylene or gases rich in propylene with oils of the character indicated above for the production of valuable oils, especially Diesel oils. This particular embodiment of the invention is especially useful and advantageous in view of the fact that large quantities of propylene are usually available in refineries having little value as such and are difficult to convert into normally liquid hydrocarbons by prior conversion methods.

45 The products produced in accordance with our invention comprise high octane number aviation gasoline, and higher boiling oils of marked utility. Such higher boiling oils represent suitable fuels for Diesel engines having high cetane numbers, as well as superior charging stocks for catalytic cracking operations.

50 In practicing our invention, olefinic gases are contacted with non-residual oils of the character

aforesaid in the presence of anhydrous aluminum chloride or other aluminum halide catalyst at temperatures not higher than about 250° F. but preferably above about 100° F. and under low or atmospheric pressure, usually not exceeding 100 pounds per square inch. The process is advantageously conducted by leading a stream of the gases into and through a body of the oil, containing aluminum chloride, in a suitable reaction vessel, and withdrawing from the vessel the gases not consumed in the reaction together with any volatile products produced during reaction which may readily be removed from effluent gases by absorption or condensation. Under ordinary conditions the boiling range of the products will run from approximately 100° F. to about 700° F. Those products which are not removed with the effluent gases remain in the reaction vessel and may be withdrawn continuously or intermittently as desired. When the reaction is once started it proceeds indefinitely so long as the supply of gases and oil is maintained, and with suitable replenishment of the catalyst. Ordinarily the amount of catalyst maintained in the catalyst zone will run from 5 to 25 per cent by weight, based on the amount of oil charged to the reaction zone. However, the actual consumption of catalyst in the process is far lower. It is ordinarily necessary only to supply sufficient catalyst to replace that necessarily withdrawn from the reaction vessel in suspension in the heavy products.

The liquid oil withdrawn from the reaction vessel is ordinarily subjected to distillation after mechanical separation of suspended solids, including the catalyst. Distillation is conducted as desired, usually to separate the oil into a gasoline fraction and a higher boiling fraction, but intermediate cuts may be taken off whenever it is desired to do so. The high boiling fraction recovered in the aforesaid distillation may, as indicated above, be used as such, for example as Diesel fuel oil, but alternatively may be subjected to catalytic cracking, especially in the presence of aluminum chloride. While fresh anhydrous aluminum chloride may be used in this subsequent cracking operation, we have found that the catalyst sludge separated from the products leaving the initial reaction zone may be advantageously used in the subsequent cracking operation.

This cracking operation is ordinarily conducted by simply distilling the high boiling oil in the presence of the catalyst and removing and condensing the vaporized products leaving the still. The distillation is ordinarily carried to a point where the residue remaining in the still is dry. One of the advantages achieved by means of our process is the fact that the gasoline produced in the subsequent cracking operation represents a fully saturated high octane number product containing large quantities of isoparaffinic constituents and may be used alone or blended with other fuels as, for example, the gasoline distillate produced in the initial reaction.

In a typical continuous embodiment of our process where high boiling oil, fresh catalyst and refinery gases are continuously supplied to the reaction zone and unreacted gases, reaction products and used catalyst are continuously withdrawn from the reaction zone, we prefer to proportion the feed of high boiling oil and gases and to adjust the rate of withdrawal of reaction products so as to maintain in and withdraw from the reaction zone an oil having about a 35° to

45° A. P. I. gravity. In a particularly advantageous, continuous embodiment of our process, we start with refinery gases and a solar oil or the like having an A. P. I. gravity of about 25° to 30° and proportion the relative feeds of gas and oil and the withdrawal of reaction products in such manner as to maintain in and withdraw from the reaction zone a 40° A. P. I. oil.

A further way of stating our preferred procedure for continuous operation is that we prefer to use higher gas-oil feed ratios with more highly aromatic or naphthenic oil charges and with less highly olefinic gases. On the other hand we prefer to use lower gas-oil feed ratios with less highly aromatic or naphthenic oil charges and with more highly olefinic gases. Between the two extremes of, on the one hand, very highly aromatic or naphthenic oils plus low olefin-content gases and, on the other hand, relatively low aromatic or naphthenic oils plus high olefin-content gases, the ratio of gas feed to oil feed will vary over a considerable range.

An important object of our invention is to react refinery gases with aromatic or naphthenic oil distillates or the like to produce more highly paraffinic oils especially those containing large amounts or even predominating amounts of isoparaffins. The above-stated preferred conditions of continuous operation have been found by us to be most conducive to the attainment of this object.

In order that our invention may be clearly set forth and understood we now describe, with reference to the drawing accompanying and forming a part of this specification, a specific manner and embodiment in which our invention may be practiced and embodied. In this drawing, the single figure is a more or less diagrammatic elevational view of apparatus suitable for carrying out the process of our invention.

Referring to the drawing, a slurry of aluminum chloride in solar oil or the like is introduced from a suitable source (not shown) through a line 1 into a high speed contactor 2, which may be equipped with any suitable means (not shown) for recirculation and for maintaining the contents at a suitable temperature, advantageously 100° to 250° F. Refinery gases from a source not shown are introduced through a line 3 into contactor 2 and therein intimately contacted with the above-mentioned slurry. A mixture of slurry, reaction products and unreacted gases is withdrawn through a line 4 and introduced into a separator 5 provided with a cone-shaped bottom 6, a weir 7 and a sight device 8. Vapors and gases from the slurry rise through the fractionating column 9 and unreacted gases leave the system through the line 10. Liquefiable hydrocarbons are condensed in column 9 and refluxed to separator 5. To assist in separating the unreacted gases from the condensable products, and also to supply make-up oil, solar oil or other naphthenic or aromatic high boiling oil is introduced into the top of column 9 through the line 11.

In the separator 5 the heavier aluminum chloride slurry settles into the bottom cone section 6 and the reaction products overflow weir 7 and are drawn off through the line 12 by means of the pump 13. Control of the oil level is had by sight device 8. The aluminum chloride slurry which has settled to the bottom is drawn off, together with some oil, through the line 14. Part of the slurry and oil is recirculated by the pump 15 through the line 16 to line 1 and thus back to

contactor 2. Another part is completely removed from the system through the line 17. This latter portion may then be used as a catalyst for cracking the high boiling portion of the reaction products as subsequently described.

The greater part of the reaction products, free from aluminum chloride, is introduced through line 12 by pump 13 into the fractionating column 20 where the products are separated into a distillate of aviation gasoline, which is withdrawn through the line 21, and a higher boiling portion, which is withdrawn through the line 22. Part of this higher boiling portion of the reaction products is pumped by the pump 23 through the line 24 to line 16 and thus through line 1 back to contactor 2. Another part is removed from the system through the line 25 and may be further fractionated to produce heavier oil fractions than aviation gasoline for use as high cetane Diesel fuel or superior charging stock for cracking, or both. Such cracking is advantageously carried out by heating with the aluminum chloride sludge removed from the system through line 17, as mentioned above.

The following specific examples will serve further to illustrate the practice and advantages of our invention:

Example 1.—This example is illustrative of the reaction between refinery gases in which C₄ hydrocarbons predominate, and high boiling oils in which naphthenic hydrocarbons predominate. The refinery gases used in this example analyzed as follows:

Per cent by volume		
Air	1.1	35
H ₂ , CH ₄	Nil	
C ₂ H ₄ , C ₂ H ₆	Nil	
C ₃ H ₆ , C ₃ H ₈	3.4	
C ₄ H ₆ , C ₄ H ₁₀	95.3	
Acid gas	Nil	
Unsaturation	74.0	

The high boiling oil used in this example was a solar oil distillate from Gulf coastal crude in which naphthenic hydrocarbons predominate. There are some aromatic hydrocarbons also present in this type of oil. The solar oil distillate had the following inspection:

Gravity	°A. P. I.	27.0
Distillation, A. S. T. M.:		
Over point	°F.	470
End point	°F.	660
10% at	°F.	500
50%		546
90%		648

2500 parts by volume of the solar oil (amounting to approximately 2225 parts by weight) were charged to a reaction vessel equipped with a stirrer. 50 parts by weight of anhydrous aluminum chloride were added to the oil. The temperature of the contents of the flask was brought to 180° F., with vigorous stirring. At this time, aluminum chloride had formed a slurry with a portion of the oil and was suspended throughout the body of the oil. The refinery gases, analyzing as above, were slowly and continuously added to the vessel. The temperature was held in the range of 180° F. to 200° F. at atmospheric pressure. From time to time, fresh aluminum chloride, as such, or as a slurry, was added in small increments sufficient to maintain the desired rate of reaction. At the end of 76 hours, the reaction was stopped. At that time a total of 170 parts by weight of aluminum chloride had been added. During the course of the reaction, 675

parts by volume of low boiling, liquid hydrocarbons were recovered by condensation from the exit gases. These low boiling hydrocarbons had the following inspection:

5	Gravity	°A. P. I.	56.9
Distillation, A. S. T. M.:			
10	Over point	°F.	126
	End point	°F.	270

	50%		200
	90%		240

Octane No. C. F. R.—A. S. T. M.	Above 90
Gum and corrosion:	

15	Mg./100 cc	13

The oily reaction product remaining in the reaction vessel amounted to 11,400 parts by volume, and had the following inspection:

20	Gravity	°A. P. I.	39.4
Distillation, A. S. T. M.:			
25	Over point	°F.	156
	End point	°F.	705
	10% at	°F.	358
	50%		560
	90%		680
	Recovery	Per cent	93

Example 2.—2500 parts by volume of the 39.4° A. P. I. oily reaction product obtained in Example 1 were charged to the same apparatus of Example 1. The same quantity of aluminum chloride as in Example 1 was added and the contents of the reaction vessel were brought to 180° F., with vigorous stirring. Refinery gases as used in Example 1 were slowly and continuously led into the vessel while holding the temperature at 180° F. to 200° F. at atmospheric pressure. At the end of 72 hours, the reaction was stopped. During this time, a total of 100 parts by weight of aluminum chloride were added. 1740 parts by volume of low boiling, liquid hydrocarbons were recovered from the exit gases during this 72 hour reaction period. These low boiling hydrocarbons had the following inspection:

45	Gravity	°A. P. I.	55.3
Distillation, A. S. T. M.:			
50	Over point	°F.	118
	End point	°F.	295
	10% at	°F.	158
	50%		195
	90%		250

Octane No., C. F. R.—A. S. T. M.	Above 90
Gum and corrosion:	

55	Mg./100 cc	7

The oily reaction product remaining in the vessel amounted to 10,800 parts by volume, with the following inspection:

60	Gravity	°A. P. I.	42.0
Distillation, A. S. T. M.:			
65	Over point	°F.	155
	End point	°F.	700
	10% at	°F.	390
	50%		594
	90%		690
	Recovery		94

Example 3.—2500 parts by volume of the 42.0° A. P. I. oily reaction product obtained in Example 2 were charged to the same apparatus of Example 1 along with the same quantity of aluminum chloride as employed in the previous example. Refinery gases as used in Examples 1 and 2 were led into the reaction vessel and the contents were held at a temperature of 180° F. to 200° F. for a

period of 68 hours. Approximately 90 parts by weight of aluminum chloride were added at intervals. During the course of the reaction, 1170 parts by volume of low boiling, high octane number liquid hydrocarbons were obtained from the exit gases. The oil remaining in the flask amounted to 10,800 parts by volume with the following inspection:

Gravity	°A. P. I.	41.9	10
Distillation, A. S. T. M.:			
Over point	°F.	234	
End point	°F.	676	
10% at	°F.	366	
50%		565	15
90%		672	
Recovery	Per cent	98	

A portion of this oil was charged to a stirring still and distilled in the presence of 5 per cent by weight of aluminum chloride. The overhead distillate amounted to 70 per cent of the oil charged and had the following inspection:

Gravity	°A. P. I.	62.0	25
Distillation, A. S. T. M.:			
Over point	°F.	78	
End point	°F.	610	
10% at	°F.	132	
50%		295	
90%		520	
Recovery	Per cent	96	30

This distillate was then fractionated to give a 36 per cent yield of gasoline having the following inspection:

Gravity	°A. P. I.	69.5	35
Distillation, A. S. T. M.:			
Over point	°F.	126	
End point	°F.	312	
10% at	°F.	159	
50%		201	40
90%		256	
Recovery	Per cent	98	
Octane No., C. F. R.-A. S. T. M.		80.5	
Gum and corrosion:			
Mg./100 cc		2	45

Example 4.—This example is illustrative of the reaction between refinery gases in which C₃ hydrocarbons predominate, and high boiling naphthenic type oils. The refinery gases used in this example analyzed as follows:

	Per cent by volume	
Air, hydrogen, methane	Nil	
Ethane, ethylene	10.9	
Propane, propylene	60.7	
i-Butane, butylene	28.3	55
n-Butane	Nil	
Acid gas	0.1	
Unsaturates	43.4	

The high boiling oil used was a solar oil similar to that in Example 1.

2,500 parts by volume of the solar oil were charged to a reaction vessel equipped with a stirrer. A weight of anhydrous aluminum chloride same as before was added to the oil in the reaction vessel. The temperature of the contents of the reaction vessel was then brought to approximately 135° F., with vigorous stirring. The C₃ refinery gases were slowly and continuously added to the reaction vessel while the contents were held within the temperature range of 125° F. to 145° F. From time to time, fresh aluminum chloride, as such, or as a slurry in solar oil, was added in small increments sufficient to maintain the desired rate of reaction. At the end of 120 hours, 75

the reaction was stopped. At that time a total of 370 parts by weight of aluminum chloride had been added. No low boiling liquid hydrocarbons were recovered from the exit gases during the run. 10,000 parts by volume of highly paraffinic oil were drawn from the flask. This oil, which was a high cetane number Diesel fuel type of product, had the following inspection:

Gravity	°A. P. I.	38.6
Distillation, A. S. T. M.:		
Over point	°F.	246
End point	°F.	688
10% at	°F.	439
50%		606
90%		688

Thus it will be observed that by reacting refinery gases in which C₃ hydrocarbons predominate with a highly naphthenic solar oil, a large yield of excellent Diesel fuel oil can be advantageously made.

Example 5.—This example is illustrative of the reaction between refinery gases and high boiling oils in which aromatic hydrocarbons largely predominate. The high boiling oil used in this example was that portion of kerosene soluble in liquid sulfur dioxide. As is well known, liquid sulfur dioxide extracts the aromatic hydrocarbons. The particular aromatic oil used in this example had the following test:

Gravity	°A. P. I.	24.8
Distillation, A. S. T. M.:		
Over point	°F.	360
End point	°F.	545
10% at	°F.	385
50%		437
90%		492

The refinery gases used in this example were the same as used in Example 4. 2500 parts by volume of the aromatic oil were charged to a reaction vessel equipped with a stirrer. Again 50 parts by weight of anhydrous aluminum chloride were added to the oil in the reaction vessel. The temperature was then brought to approximately 140° F., with vigorous stirring. The refinery gases were slowly and continuously added to the vessel while the contents were held within the temperature range of 135° F. to 155° F. From time to time fresh aluminum chloride, as such, or as a slurry, was added in small increments sufficient to maintain the desired rate of condensation. At the end of 96 hours, the reaction was stopped. At that time a total of 200 parts by weight of aluminum chloride had been added. No low boiling liquid hydrocarbons were recovered from the exit gases during the run. 11,000 parts by volume of highly paraffinic oil were drawn from the reaction vessel. This oil had the following inspection:

Gravity	°A. P. I.	37.1
Distillation, A. S. T. M.:		
Over point	°F.	155
End Point	°F.	700
10% at	°F.	430
50%		606
90%		700

The high A. P. I. gravity of the reaction product indicates a high content of paraffinic hydrocarbons. Thus it will be observed that by this reaction, aromatic hydrocarbons are converted into paraffinic hydrocarbons.

While we have described our invention with particular regard to certain specific embodiments and examples, our invention is not limited to such

examples or embodiments except as defined in the appended claims.

What we claim is:

1. The process of producing highly paraffinic synthetic oils, which comprises subjecting olefin-containing gases and non-residual hydrocarbon oil, high in non-paraffinic and non-asphaltic constituents, and substantially free from hydrocarbons boiling within the gasoline boiling-point range, to contact with each other in the presence of an aluminum halide catalyst, at a temperature not higher than about 250° F.

2. The process of producing highly paraffinic synthetic oils, which comprises continuously passing a stream of olefin-containing gases through a body of non-residual hydrocarbon oil, high in non-paraffinic and non-asphaltic constituents and substantially free from hydrocarbons boiling within the gasoline boiling point range, in a reaction zone maintained at a temperature of not more than about 250° F., in the presence of an aluminum chloride catalyst, supplying additional oil and catalyst to the reaction zone, and removing effluent gases and liquid reaction products from the reaction zone as formed.

3. The process of claim 1, wherein the oil consists substantially entirely of constituents boiling between 400° and 700° F.

4. The process of claim 1 wherein the oil is a solar oil distillate recovered from a naphthenic crude oil.

5. The process of claim 1 wherein the oil is an SO₂ extract of kerosene distillate from a naphthenic crude oil.

6. The process of claim 1 wherein the gases contain at least 30 per cent by volume of unsaturated hydrocarbons.

7. The process of claim 1 wherein the gases predominate in propylene.

8. A continuous process for producing paraffinic oils including substantial amounts of iso-paraffinic hydrocarbons boiling in the gasoline boiling point range from refinery gases and oils which are non-paraffinic in character, which comprises reacting a refinery gas containing not less than about 30 per cent by volume of olefins with a non-residual, non-asphaltic hydrocarbon oil of non-paraffinic character having an A. P. I. gravity not greater than about 30° and largely free from hydrocarbons boiling in the gasoline boiling point range in the presence of aluminum chloride, maintaining a reaction temperature between about 100° and 250° F., continuously supplying said gas and said oil to the reaction mixture and replenishing the aluminum chloride, continuously removing from the reaction mixture unreacted gases, used aluminum chloride, a gasoline fraction of substantially paraffinic

character having a high octane number and containing considerable amounts of iso-paraffins, and an oil fraction of higher boiling range than said gasoline fraction which is largely paraffinic in character and has an A. P. I. gravity between about 35° and 45°.

9. The process of claim 8 wherein said non-asphaltic hydrocarbon oil of non-paraffinic character is a solar oil distillate recovered from a naphthenic crude oil.

10. The process of claim 8 wherein said refinery gas contains propylene as the predominant olefin.

11. The process of claim 8 wherein at least a portion of said oil fraction of 35° to 45° A. P. I. gravity is distilled in the presence of aluminum chloride and a fraction is separated from the distillate consisting of gasoline boiling point range paraffin hydrocarbons.

12. A process of producing high octane number gasoline which comprises contacting refinery gases containing substantial amounts of olefins with a non-residual, non-asphaltic hydrocarbon oil of non-paraffinic character, substantially free from gasoline boiling point range hydrocarbons,

25 in the presence of aluminum chloride at temperatures not above about 250° F., thereby forming a reaction product which is lighter and more paraffinic than the initial oil, and at least partly converting the aluminum chloride into a sludge, separating unreacted gases and a substantially saturated, paraffinic high octane number gasoline fraction from said reaction product, and distilling at least a portion of the remainder of said reaction product in the presence of said aluminum chloride sludge, thereby producing a further quantity of saturated, high octane number paraffinic gasoline.

13. A process of producing high cetane number Diesel fuel from refinery gases and hydrocarbon oils of relatively poor motor fuel value, which comprises contacting refinery gases containing substantial quantities of olefins with a non-residual, non-asphaltic hydrocarbon oil of non-paraffinic character in the presence of aluminum chloride at temperatures not greater than about 250° F., thereby producing a lighter oil of essentially paraffinic character, separating unreacted gases, gasoline and aluminum chloride from said oil, and fractionating the remaining oil to produce a paraffinic cut of high cetane number and of boiling point and volatility range suitable for Diesel fuel.

14. The process of claim 13 wherein the refinery gases contain propylene as the predominant olefin.
